[57] CLAIM

The ornamental design for a fuse holder, as shown and described.

DESCRIPTION

FIG. 1 is a perspective view of a fuse holder showing my new design.

FIG. 2 is a top plan view of the fuse holder on an enlarged scale.

FIG. 3 is a front elevational view thereof on an enlarged scale.

FIG. 4 is a side elevational view thereof on an enlarged scale.

FIG. 5 is a bottom view thereof on an enlarged scale. The electrical wires and interior fuse chips are shown in broken lines for illustrative purposes only.
